CLAIM

The ornamental design for a medical dressing, as shown and described.

DESCRIPTION

The present application is an application for reissue of U.S. Design Pat. No. D691,730, filed Nov. 14, 2012, which claims priority to Registered Community Design No. 002041673, filed May 15, 2012.

FIG. 1 is a perspective view of a medical dressing.

FIG. 2 is a top view of the medical dressing of FIG. 1.

FIG. 3 is a bottom view of the medical dressing of FIG. 1.

FIG. 4 is a front view of the medical dressing of FIG. 1.

FIG. 5 is a rear view of the medical dressing of FIG. 1. FIG. 6 is a right side view of the medical dressing of FIG. 1; and,

FIG. 7 is a left side view of the medical dressing of FIG. 1. *FIG. 8 is a perspective view of another embodiment of a medical dressing.*

FIG. 9 is a top view of the medical dressing of FIG. 8.

FIG. 10 is a bottom view of the medical dressing of FIG. 8.

FIG. 11 is a front view of the medical dressing of FIG. 8.

FIG. 12 is a rear view of the medical dressing of FIG. 8. *FIG. 13 is a right side view of the medical dressing of FIG. 8; and,*

FIG. 14 is a left side view of the medical dressing of FIG. 8.

The broken lines shown in the drawings illustrate features that form no part of the claimed design.

1 Claim, 14 Drawing Sheets

Matter enclosed in heavy brackets [ ] appears in the original patent but forms no part of this reissue; matter printed in italics indicates the additions made by reissue.
